RAILWAY SIGNALING SYSTEM

Henry S. Young, Wilkinsburg, and Ronald A. McCann, Swissvale, Pa., assignors to The Union Switch & Signal Company, Swissvale, Pa., a corporation of Pennsylvania

Application April 30, 1941, Serial No. 391,104

7 Claims. (Cl. 246—33)

Our invention relates to railway signaling systems and particularly to a system for the control of signals on stretches of single track over which traffic normally moves in both directions.

In the signaling systems employed on stretches of track over which traffic moves in both directions it is necessary for a train to control the signals in its rear to warn following trains, and to also control the signals in advance of itself to warn an approaching train of its presence.

The standard practice in absolute permissive block signaling systems is to arrange the equipment so that when a train advances beyond a passing siding, all of the signals in the track stretch between that siding and the adjacent siding in advance and controlling movement of trains in the opposite direction are caused to display their stop indications to thereby prevent a train moving in the opposite direction of traffic from advancing beyond the exit end of the adjacent passing siding.

In addition, it is customary in signaling systems of this type to arrange the signals governing each direction of traffic so that when the headblock signal at the exit end of a passing siding is displaying its stop indication, the signal at the entrance end of the siding will display a caution indication, and so that the adjacent signal in the rear thereof will also display a caution indication. This control of the signals is desirable so that when trains moving in opposite directions approach a passing siding at the same time, they will have ample warning of the approach of each other and will be able to stop before colliding even though the passing siding is relatively short.

In the systems heretofore known the signals have operated in the manner outlined above both when the headblock signal at the exit end of a siding is caused to display its stop indication because a train moving in the direction opposite to that controlled by that signal is approaching the signal, and when the signal is caused to display its stop indication because a train moving in the direction of traffic controlled by that signal is immediately in advance of the signal.

This method of operation of the signals is desirable where two trains moving in opposite directions are approaching a passing siding as it provides the relatively long braking distance necessary for both trains to stop before colliding.

However, where two trains moving in the same direction of traffic are in the track stretch in the vicinity of a passing siding the second or following does not require as much braking distance as

is necessary when two trains moving in opposite directions are approaching each other.

If the signals operate as described above when two trains traveling in the same direction are in the vicinity of a passing siding, the second or following train will be given a caution indication sooner than is necessary and the train will unnecessarily reduce its speed.

It is an object of this invention to provide an improved signaling system of the type described which operates so that a train approaching a passing siding will receive a restrictive indication at a point less distant from the rear of a train moving in the same direction than from the

front of a train traveling in the opposite direction, to thereby provide ample braking distance for trains moving in opposite directions while not unnecessarily retarding the second or following one of two trains.

20 A further object of the invention is to provide an improved signaling system of the type described which is arranged so that signals for each direction of traffic are controlled so that when the headblock signal at the exit end of a passing siding is displaying its stop indication because a train traveling in the opposite direction is approaching the signal, the first and second signals in the rear thereof will display their most restrictive proceed indications, and so that when

25 the headblock signal is displaying its stop indication because a train traveling in the direction of traffic controlled by that signal is in advance of the signal, the adjacent signal in the rear will display its most restrictive proceed indication, 30 but the second signal in the rear will display a less restrictive indication.

35 Another object of the invention is to provide a signaling system of the type described and which is arranged so that a minimum of line wires are required to obtain the desired control of the signals.

40 Other objects of the invention and features of novelty will be apparent from the following description taken in connection with the accompanying drawings.

45 We shall describe two forms of apparatus embodying our invention, and shall then point out the novel features thereof in claims.

50 In the drawings,

Fig. 1 is a diagram of a stretch of railway track equipped with one form of signaling system embodying our invention, and

55 Fig. 2 is a diagram showing a modified form of system embodying our invention.

Similar reference characters refer to similar parts in each of the two views.

Referring to Fig. 1 of the drawings, there is shown therein a stretch of single track railroad over which traffic moves in both directions. To facilitate description of the equipment it will be assumed that the right-hand end thereof is east and that the left-hand end thereof is west. Accordingly, train movements from left to right are eastbound, and train movements from right to left are westbound.

The track stretch includes passing sidings which are located at appropriate intervals and permit traffic to be diverted from the main track under the customary control of switches. One such passing siding is shown in the drawings. The switch at the left or west end of the siding is designated AW, while the switch at the right or east end of the passing siding is designated BW.

The rails of the track stretch are divided by insulated joints 3 into successive track sections designated 16T, 17T, 12T, etc. Each of these track sections is provided with a track circuit including a track battery connected across the section rails at one end of the section, and a track relay, designated TR with a suitable prefix, connected across the section rails at the other end of the section.

Eastbound traffic through the track stretch is governed by a plurality of trackway signals designated 2S, 4S, 6S, etc., while westbound traffic through the track stretch is governed by a plurality of trackway signals designated 1S, 3S, 5S, etc.

The signals shown in the drawings are of the color light type, but it should be understood that the invention is not limited to the use of signals of this type and that any appropriate form of wayside signals well known in the art may be employed.

Except as hereinafter explained in detail, each of the signals has a green or clear lamp G, a yellow or caution lamp Y, and a red or stop lamp R. The signals at the entrance ends of the passing sidings have upper portions which include the green, yellow and red lamps as illustrated in the drawings, while these signals may also have lower portions, not shown, governing movement of trains from the main track onto the passing siding.

The signals next in the rear of the signals at the entrance ends of the passing sidings include two red lamps and two green lamps as well as a yellow lamp so as to be capable of displaying a clear signal comprising a green over a red lamp, an approach medium indication comprising a yellow over a green lamp, a caution indication comprising a yellow over a red lamp, and a stop indication comprising a red over a red lamp.

The diagram which forms Fig. 1 of the drawings shows the means for controlling the signals which govern eastbound traffic including the means for controlling the signal 2S. In order to simplify the disclosure the means for controlling the signals which govern westbound traffic has not been shown, but it should be understood that this equipment is substantially the same as that shown for the eastbound signals.

The means for controlling the signal 2S includes line circuits I, II and III. The line circuit I extends from the signal 2S to a point in advance of the west end of the passing siding, while the line circuit II extends from the signal 4S at the west end of the passing siding to a point in advance of the east end of the passing

siding. The line circuit III extends from the signal 6S eastward and is controlled in the manner well known in the art by traffic conditions in the track stretch between the east end of the passing siding shown and the adjacent passing siding in advance. The supply of energy to the line circuit III may be controlled in the manner shown in United States Patent No. 1,294,736 to Sedgwick N. Wight.

10 The line circuits I and II are controlled in the manner hereinafter explained in detail so that at times both direct and alternating current energy is supplied over these circuits.

15 The track stretch is provided at appropriate locations with sources of direct current the terminals of which are designated B and C, while a source of alternating current having terminals BX and CX is provided.

20 The equipment is shown in the condition which it assumes when the track stretch is vacant, and when the switches AW and BW are positioned to direct traffic through the main track.

25 At this time as the track stretch is vacant, energy of normal relative polarity is supplied over the line circuit III to the relay 6HD and the neutral contact 20 and polar contact 21 of this relay establish the circuit of the green lamp G of signal 6S.

30 In addition, at this time neutral contact 23 establishes a circuit to supply energy to the pole changing relay 6PC and the contacts 25 and 26 of this relay are picked up.

35 As track section 14T is vacant, the track relay 14TR is picked up and its contact 28 interrupts the circuit of the eastbound directional stick relay 6ES and the contacts 30, 31 and 32 of this relay are released. As contact 32 is released, it 40 interrupts connection from the secondary winding of transformer LT to the line circuit II and establishes connection from one wire of line circuit II to terminal C of a source of direct current.

45 At this time the westbound directional stick relay 3WS is released so that connection is established from terminal B of the source of direct current through back contact 34 of relay 3WS, front contact 35 of track relay 15TR, and front contact 36 of track relay 14TR to the other wire 50 of line circuit II. Accordingly, energy is supplied to line circuit II, and as relay 6PC is picked up, this energy is of normal polarity. This energy feeds to the relay 4HD as track relays 13TR and 12TR are picked up, and as switch controlled contact AWN is closed. The contact AWN is closed when and only when the switch AW is in its normal position.

55 As a result of the supply of energy of normal polarity to the relay 4HD, neutral contact 38 and polar contact 39 cooperate to establish the circuit of the green lamp G of signal 4S, while neutral contact 40 partially establishes the pick-up circuit of eastbound directional stick relay 4ES. In addition, neutral contact 42 and polar contact 43 of relay 4HD cooperate to establish the circuit of the pole changing relay 4PC, while neutral contact 45 and polar contact 46 cooperate to establish a circuit short circuiting the primary winding of the transformer MT. This prevents inductive discharges of current from the transformer on release of the track relays governing line circuit I and thus reduces arcing at these contacts.

60 At this time one wire of line circuit I is connected through the secondary winding of trans-

former MT to terminal C of a source of direct current, while the other wire of this line circuit is connected through front contact 48 of relay 13TR and front contact 49 of relay 12TR to terminal B of the source of current so that direct current energy is supplied to the line circuit I. As the contacts 50 and 51 of relay 4PC are picked up, the energy supplied to the line circuit I is of normal polarity. This energy feeds to the relay 2HD and the neutral contact 53 and polar contact 54 of this relay cooperate to partially establish the circuit of the upper green lamp G of signals 2S, while neutral contact 55 connects the primary winding of transformer NT across the wires of line circuit I. This circuit includes a resistor RA in series therewith to limit flow of direct current in the circuit of the transformer primary winding. At this time alternating current is not supplied to the line circuit I so that no energy is supplied through the transformer NT and the associated rectifier to the relay 2CD and the contacts of this relay are released. As the contacts 57 and 58 of relay 2CD are released, contact 57 establishes the circuit of the upper green lamp G of signal 2S, while contact 58 establishes the circuit of the lower red lamp R of signal 2S. Accordingly, the signal 2S displays its clear indication which consists of a green over a red lamp.

Operation of equipment on movement of an east-bound train through the track stretch

When an eastbound train enters the track stretch at the left of the passing siding, the westbound signals for this stretch and including signal 5S are conditioned to display stop indications. The means for effecting this control of these signals is not shown, but this control may be effected in any manner well known in the art.

When the eastbound train enters section 10T, track relay 10TR releases and cuts off the supply of energy over line circuit I to relay 2HD and the neutral contacts of this relay release. Release of contact 53 of relay 2HD interrupts the circuit of the upper green lamp G of signal 2S and establishes the circuit of the upper red lamp R so that the signal 2S displays its stop indication consisting of a red over a red lamp.

When the train advances into section 11T, the track relay 11TR releases and additionally interrupts the line circuit I, while when the train enters section 12T, track relay 12TR releases and interrupts line circuits I and II. When line circuit II is interrupted, relay 4HD is deenergized and its neutral contacts release so that contact 38 interrupts the circuit of the green lamp G of signal 4S and establishes the circuit of the red lamp of this signal.

In addition, on release of the neutral contacts of relay 4HD contact 42 interrupts the circuit of the pole changing relay 4PC and the contacts 50 and 51 of this relay release so that on the subsequent supply of energy to the line circuit I the energy supplied to the relay 2HD is of reverse relative polarity.

When the train enters section 12T, track relay 12TR releases and its contact 59 establishes the pick-up circuit of the eastbound directional stick relay 4ES. This circuit includes front contact 40 of relay 4HD. However, the track relay 12TR is of a type which is relatively quick to release, while the relay 4HD is of a type the neutral contacts of which are slow to release so that the pick-up circuit of relay 4ES is momentarily com-

plete. During this period energy is supplied to the relay 4ES and its contact 62 picks up and establishes a stick circuit including back contact 59 of track relay 12TR and front contact 62 of relay 4ES for the relay winding, while another stick circuit for relay 4ES is established on release of contact 40 of relay 4HD.

On picking up of the contacts of relay 4ES contact 63 establishes a circuit shunting contact 48 of relay 13TR so that direct current energy is supplied to line circuit I as soon as the east-bound train vacates section 12T.

When the train advances into section 13T, track relay 13TR releases and additionally interrupts line circuit II.

When the rear of the train vacates sections 10T and 11T, the track relays 10TR and 11TR pick up, but contact 49 of track relay 12TR continues to interrupt line circuit I. When section 12T is vacated, track relay 12TR picks up and connection is established from terminal B of the source of current through front contact 49 of relay 12TR, and front contact 63 of relay 4ES to one wire of line circuit I, while the other wire of this line circuit is connected to terminal C of the source through the secondary winding of transformer MT.

At this time the contacts of relay 4PC are released so that the energy supplied over line circuit I to the relay 2HD is of reverse polarity. On the supply of this energy to the relay 2HD its neutral contacts pick up, while its polar contact 54 is shifted to its right-hand or reverse position. As a result of picking up of contact 53 and movement of contact 54, the supply of energy to the upper red lamp R of signal 2S is cut off, while the circuit of the upper yellow lamp Y of signal 2S is established. The signal, therefore, displays a yellow over a red lamp, which provides the caution indication.

As a result of energization of relay 2HD, contact 55 establishes the circuit of the transformer NT, but alternating current energy is not supplied to the line circuit I at this time so that relay 2CD remains released.

When the train advances into section 14T, track relay 14TR releases and its contact 28 establishes the pick-up circuit of eastbound directional stick relay 6ES so that the contacts of this relay pick up. Also, upon the release of track relay 14TR, its contact 52 opens line circuit III and deenergizes relay 6HD. The neutral contacts of relay 6HD are slow releasing so that the pick-up circuit of relay 6ES will be closed long enough for its front contact 30 to close. Upon the closing of front contact 30 of relay 6ES, a stick circuit including back contact 28 of relay 14TR is effective and upon the closing of back contact 60 of relay 6HD, a second stick circuit is closed which keeps relay 6ES energized while an eastbound train is in the block of signal 6S.

When the train enters section 15T, track relay 15TR releases and additionally interrupts line circuit III.

As a result of picking up of the contacts of relay 6ES, contact 32 establishes connection from terminal C of the source of direct current through the secondary winding of transformer LT to one wire of line circuit II, while contact 31 partially establishes connection between terminal B and the other wire of line circuit II. This connection does not become complete until the train vacates section 14T and track relay 14TR picks up and is traced from terminal B

through back contact 34 of relay 3WS, front contact 31 of relay 6ES, and front contact 36 of track relay 14TR.

Accordingly, when section 14T is vacated, direct current is supplied to line circuit II, and this energy is of reverse polarity as the relay 6PC is released, while alternating current is also supplied to line circuit II as the secondary winding of transformer LT is included in series with the line circuit.

On the supply of direct current of reverse polarity to relay 4HD its neutral contacts pick up, while its polar contacts are shifted from their left-hand or normal positions to their right-hand or reverse positions. At this time the primary winding of transformer MT is connected across the wires of line circuit II by a circuit which is traced from one line wire through resistor RB, reverse polar contact 46, and front neutral contact 45 of relay 4HD to one terminal of the primary winding of transformer MT, the other terminal of which is connected to the other line wire of line circuit II. Accordingly, alternating current supplied to the line circuit II is supplied through the transformer MT to the line circuit I, while resistor RB substantially prevents flow of direct current in the transformer primary winding.

When track relay 13TR picks up, its contact 48 is closed to establish connection from terminal B of the source of direct current to one wire of line circuit I after release of contact 63 of relay 4ES. On picking up of contact 40 of relay 4HD the stick circuit of relay 4ES is interrupted and its contacts 62 and 63 release.

At this time contact 43 of relay 4HD is in its reverse position so that energy is not supplied to pole changing relay 4PC even though contact 42 is picked up. Accordingly, the direct current energy supplied to relay 2HD continues to be of reverse relative polarity.

As a result of the supply of alternating current energy to the line circuit I, energy is supplied through the transformer NT and the associated rectifier to the relay 2CD and the contacts of this relay are picked up to thereby maintain the upper yellow lamp lighted while extinguishing the lower red lamp and lighting the lower green lamp. The signal 2S, therefore, displays its approach medium indication consisting of a yellow over a green lamp.

At this time as neutral contact 38 of relay 4HD is picked up and polar contact 39 of this relay is in its right-hand or reverse position, the yellow lamp Y of this signal is lighted to provide the caution indication.

It will be seen, therefore, that as soon as the eastbound train vacates section 12T, signal 2S is conditioned to display its caution indication, and that when the train vacates section 14T, signal 4S is conditioned to display its caution indication, while signal 2S is conditioned to display its approach medium indication.

Accordingly, a second or following train will receive an indication of traffic conditions in advance from signal 2S, but will not be required to greatly reduce its speed until it reaches signal 4S at which point it will receive a caution indication. The second or following train, therefore, will not unnecessarily reduce its speed at signal 2S, but will continue until it reaches 4S, while after reaching signal 4S the train will have sufficient distance in which to stop without running into the rear of the preceding train. At this time the braking distance required by the sec-

ond train is determined only by its own stopping distance since the preceding train is moving in the same direction, or is standing still, and the two trains are not approaching each other.

- 5 When the first train advances beyond signal 8S, this signal is caused to display its stop indication, while energy of reverse relative polarity is supplied by means not shown to the line circuit III so that when the train vacates sections 10 15T and 16T, this energy feeds to the relay 6HD. As a result, neutral contact 20 and polar contact 21 establish the circuit of the yellow or caution lamp Y of signal 6S, while contact 23 establishes the circuit of the relay 6PC. In addition, contact 69 of relay 6HD interrupts the holding circuit of relay 6ES and the contacts of this relay release.

On release of contact 32 of relay 6ES one wire of line circuit II is connected directly to terminal C of the source of direct current instead of being connected through the secondary winding of transformer LT. Accordingly, the supply of alternating current to the line circuit II is cut off, and energy is no longer supplied through the transformer MT to line circuit I and to the relay 2CD so that the contacts of this relay release.

At this time the other wire of line circuit II is connected to terminal B of the source of current through front contact 36 of track relay 14TR, front contact 35 of track relay 15TR, and back contact 34 of directional stick relay 3WS so that energy is supplied to line circuit II and to relay 4HD. As the contacts of relay 6PC are picked up, the energy supplied to the relay 4HD is of normal relative polarity and polar contact 39 of relay 4HD is shifted from its reverse to its normal position to thereby extinguish the yellow lamp Y and light the green lamp G of signal 4S.

In addition, at this time polar contact 43 of relay 4HD establishes the circuit of the relay 4PC, while polar contact 46 establishes the circuit to short circuit the primary winding of transformer MT. As relay 4PC is energized, the energy supplied to relay 2HD is changed from reverse to normal polarity and contact 54 is shifted from its reverse to its normal position, while at this time relay 2CD is released as explained above. Accordingly, the upper green lamp G and the lower red lamp R of signal 2S are lighted so that this signal provides its clear indication.

When the train advances beyond the signal next in advance of signal 8S, the energy supplied to relay 6HD is changed from reverse to normal polarity so that contact 21 interrupts the circuit of the yellow lamp Y and establishes the circuit of the green lamp G of signal 6S, while contact 23 maintains the circuit of relay 6PC so that energy of normal polarity is supplied to line circuit II and signals 4S and 2S continue to display their clear indications.

Operation of system on movement of a westbound train through the track stretch

65 When a westbound train leaves the passing siding next in the east of the siding shown, the supply of energy to the line circuit III is cut off in the manner well known in the art.

As a result of deenergization of relay 6HD, contact 20 establishes the circuit of the red lamp R of signal 6S to prevent an eastbound train proceeding beyond the passing siding. In addition, on release of relay 6HD contact 23 interrupts the circuit of the relay 6PC so that its contacts release and change the polarity of the

energy supplied over line circuit II from normal to reverse. On release of contact 60 of relay 6HD the pick-up circuit of eastbound directional stick relay 6ES is interrupted and contacts 31 and 32 of this relay remain released so that alternating current energy is not supplied to the line circuit II.

At this time one line wire of line circuit II is connected to terminal B of the source through front contact 36 of track relay 14TR, front contact 35 of track relay 15TR, and back contact 34 of directional relay 3WS, while the other line wire of line circuit II is connected through back contact 32 of relay 6ES to terminal C so that relay 4HD is energized and its polar contact 39 establishes the circuit of the yellow lamp Y of signal 4S. In addition, polar contact 43 interrupts the circuit of relay 4PC so that energy of reverse polarity is supplied over line circuit I to relay 2HD. At this time polar contact 46 of relay 4HD connects the primary winding of transformer MT across the wires of line circuit II, but as alternating current is not being supplied to line circuit II, no energy is supplied through this transformer to the line circuit I and relay 2CD remains released. As relay 2CD is released and relay 2HD is supplied with energy of reverse polarity, the upper yellow lamp Y and the lower red lamp R of signal 2S are lighted so that signal 2S provides its caution indication.

It will be seen, therefore, that when a westbound train is approaching the passing siding, signal 6S displays its stop indication, while signals 4S and 2S display caution indications. Accordingly, an eastbound train will begin to reduce its speed when it reaches signal 2S and will have adequate space in which to stop before colliding with the westbound train, even if the westbound train should continue beyond signal 3S before stopping.

When the westbound train enters section 15T, contact 35 of track relay 15TR releases and interrupts line circuit II to thereby cut off the supply of energy to relay 4HD.

On interruption of the supply of energy to the relay 4HD the neutral contacts of this relay release and contact 36 establishes the circuit of the red or stop lamp R of signal 4S. Release of relay 4HD does not affect the supply of energy to line circuit I and energy of reverse polarity continues to be supplied to the relay 2HD so that the signal 2S continues to display its caution indication.

When the westbound train under consideration advances into section 14T, track relay 14TR releases and its contact 65 establishes the pick-up circuit of the westbound directional stick relay 3WS. This circuit includes front contact 66 of relay 3HD which controls the signal 3S in the same manner that relay 4HD controls signal 4S. On the supply of energy to relay 3WS its contact 67 picks up and establishes a stick circuit including back contact 65 of track relay 14TR for relay 3WS, while on release of contact 66 of relay 3HD another stick circuit is established for relay 3WS and the contacts of this relay remain picked up as long as contact 66 of relay 3HD remains released.

As a result of picking up of contact 34 of relay 3WS, the supply of energy to the line circuit II and to relay 4HD is additionally interrupted.

When the westbound train enters section 14T, contact 28 of relay 14TR is released, but at this time the pick-up circuit of relay 6ES is 75

interrupted by contact 60 of relay 6HD so that relay 6ES remains released.

When the westbound train enters section 13T, track relay 13TR releases and its contact 48 interrupts the supply of energy to line circuit I so that relay 2HD releases and contact 53 establishes the circuit of the upper red lamp R of signal 2S. This signal, therefore, displays a red lamp over a red lamp to provide the stop indication.

If the westbound train continues beyond signal 5S, track relay 12TR will release and interrupt line circuit I, while in similar manner track relays 11TR and 10TR will release when the train enters these sections. These track relays interrupt line circuit I and thus cause signal 2S to continue to display its stop indication.

From the foregoing it will be seen that when a train traveling in one direction advances beyond a passing siding, the signals in the rear of that train and controlling train movements in that direction are governed in such manner that the signal at the entrance end of the passing siding will display its caution indication, while the adjacent signal in the rear thereof will display its approach medium indication. This provides a following train with a warning of the presence of the first train without requiring the following train to reduce its speed before it is necessary to do so.

On the other hand, when a train moving in one direction is approaching the passing siding, the signals governing movement of trains in the other direction are controlled in such manner that the signal at the other end of the passing siding and the signal next in the rear thereof both display caution indications so that a second train moving in said other direction will have ample warning of the presence of the first train and will stop before colliding with that train.

It will be seen also that the control of the signals is arranged in such manner that a minimum of line wires are required since the approach medium signal indication is provided by superimposing alternating current on the existing line circuits.

Construction of system shown in Fig. 2

50 In Fig. 2 of the drawings there is shown a modified system for securing the same control of the signals as is provided by the system shown in Fig. 1.

The system shown in Fig. 2 is similar to that shown in Fig. 1, and differs therefrom in that coded energy instead of alternating current energy is supplied to the line circuits at times to provide an additional proceed indication.

The equipment is shown in Fig. 2 in the condition which it assumes when the track stretch is vacant. At this time direct current energy is supplied over line circuit III to relay 6HD so that contacts 20 and 21 of this relay establish the circuit of the green lamp G of signal 6S.

55 At this time contact 28 of track relay 14TR interrupts the circuit of eastbound directional stick relay 6ES so that contacts 31 and 32 are released. Contact 32, therefore, interrupts the circuit of code transmitter 11CT and this device is deenergized. Contact 31 of relay 6ES establishes connection from one wire of line circuit II to terminal C of a source of direct current, while the other wire of this line circuit is connected through contact 36 of relay 14TR, contact 35 of relay 15TR, and contact 34 of relay 3WS to

terminal B of the source so that energy is supplied to line circuit II. This energy is of normal relative polarity as the pole changing relay 6PC is energized by current supplied over contact 23 of relay 6HD.

The energy supplied to the line circuit II feeds to the relay 4HD and contacts 38 and 39 of this relay cooperate to establish the circuit of the green lamp G of signal 4S, while contacts 42 and 43 cooperate to establish the circuit of the pole changing relay 4PC. As contact 42 of relay 4HD is picked up, the circuit of the primary winding of decoding transformer 4DT is interrupted and the relay 4H is released. In addition, contact 70 of relay 4HD interrupts the circuit of the relay 4CR, while contact 71 interrupts the circuit of the code transmitter ICT.

At this time one wire of line circuit I is connected to terminal C of a source of direct current through front contact 51 of relay 4PC and front contact 12 of relay 4HD, while the other wire of line circuit I is connected through front contact 50 of relay 4PC, front contact 73 of relay 4HD, front contact 48 of relay 13TR, and front contact 49 of relay 12TR to terminal B of the source. Accordingly, energy is supplied to the line circuit I, and as the contacts of relay 4PC are picked up, this energy is of normal relative polarity and the relay 2HD is energized.

At this time, therefore, contact 77 of relay 2HD interrupts the circuit of the code following relay 2CR, while contact 78 interrupts the circuit of the primary winding of decoding transformer 2DT and establishes a circuit to energize a relay 2DP. As relay 2DP is energized, its contact 80 is picked up and cooperates with the polar contact 54 of relay 2HD and contact 57 of relay 2H to establish the circuit of the upper green lamp G of signal 2S, while contact 58 of relay 2H establishes the circuit of the lower red lamp R of signal 2S.

Operation of system shown in Fig. 2 on movement of an eastbound train through the track stretch

When an eastbound train, that is a train moving from left to right, enters section 10T, the track relay 10TR releases and interrupts line circuit I so that relay 2HD releases and its contact 78 interrupts the circuit of relay 2DP. Accordingly, contact 80 of relay 2DP releases and establishes the circuit of the upper red lamp R of signal 2S to thereby condition this signal to display its stop indication.

When the train advances into section 11T, the track relay 11TR releases and additionally interrupts line circuit I, while when the train enters section 12T, track relay 12TR releases and interrupts line circuit II, and its contact 49 interrupts line circuit I. In addition, contact 59 of relay 12TR establishes the pick-up circuit of eastbound stick relay 4ES so that contact 62 of relay 4ES picks up and establishes a stick circuit for the relay 4ES. The pick-up circuit is interrupted on release of contact 40 of relay 4HD, but release of contact 40 establishes another stick circuit for relay 4ES.

As a result of interruption of line circuit II, relay 4HD releases and its contact 38 establishes the circuit of the red or stop lamp R of signal 4S. This circuit includes, in addition, back contact 82 of relay 4H. On release of relay 4HD contact 42 interrupts the circuit of relay 4PC and establishes the circuit of the primary winding of the decoding transformer 4DT, while contact 70 con-

nects the relay 4CR across the line circuit II. As line circuit II is interrupted by track relay 12TR, the relay 4CR remains released, while as relay 4PC is released, its contact 59 interrupts the circuit of code transmitter ICT.

The code transmitter ICT has a contact 75 which when the device is energized is alternately opened and closed at a rate such as to provide a number of energy impulses each minute, such as 75 a minute, which are separated by periods of equal duration in which no energy is supplied. While the supply of 75 energy impulses a minute is mentioned, this is illustrative only and any desired frequency of energy impulses may be employed.

When the train advances into section 13T, track relay 13TR releases and additionally interrupts line circuits I and II, while when the train enters section 14T, track relay 14TR releases and its contact 28 establishes the pick-up circuit of relay 6ES so that its contacts 31 and 32 pick up and contact 36 of relay 14TR interrupts line circuit II. As a result of picking up of contact 32, the circuit of the code transmitter IICT is established, while contact 31 establishes connection from one line wire of line circuit II through code transmitter contact 75 to terminal C of the source. At this time, however, connection from the other wire of the line circuit to terminal B is interrupted by contact 36 of relay 14TR so that energy is not supplied to the line circuit.

On release of relay 14TR its contact 28 establishes the pick-up circuit of relay 6ES and contact 30 of relay 6ES thereupon picks up and establishes a stick circuit for the relay.

In addition, on release of track relay 14TR its contact 52 interrupts line circuit III so that relay 6HD releases and its contact 60 interrupts the pick-up circuit and establishes the stick circuit for relay 6ES to thereby insure that relay 6ES will remain energized after contact 28 of relay 14TR is picked up.

As a result of release of relay 6HD, contact 20 establishes the circuit of the red or stop lamp R of signal 6S, while contact 23 releases and interrupts the circuit of the relay 6PC.

When the train vacates section 12T, track relay 12TR picks up and establishes a circuit for supplying energy to the line circuit I. At this time one wire of this line circuit is connected through back contact 50 of relay 4PC to terminal C, while the other wire of the line circuit is connected through back contact 51 of relay 4PC, front contact 63 of relay 4ES, and front contact 49 of relay 12TR to terminal B of the source. Accordingly, energy is supplied to line circuit I, and the connections are arranged so that the energy supplied to the relay 2HD is of reverse polarity. On picking up of relay 2HD a circuit is established to energize the relay 2DP so that its contact 80 picks up, while polar contact 54 is shifted to its reverse position with the result that the upper red lamp R of signal 2S is extinguished and the upper yellow lamp Y is lighted to thereby cause this signal to display its yellow over red or caution indication.

When the train vacates section 13T, the track relay 13TR picks up, but line circuit II continues to be incomplete until track relay 14TR is picked up. When the train vacates section 14TR, connection is established from one wire of line circuit II through front contact 36 of track relay 14TR, front contact 84 of relay 6ES, and back contact 34 of relay 3WS to terminal B, while the other wire of the line circuit II is connected

through front contact 31 of relay 6ES and code transmitter contact 75 to terminal C so that impulses of coded energy are supplied to the line circuit II.

The coded energy supplied to line circuit II feeds to the relays 4HD and 4CR. The relay 4HD is of a type which is relatively slow acting with the result that its neutral contacts remain released when coded energy is supplied to the relay. The coded energy supplied to relay 4CR produces code following operation of the relay and energy is supplied through the decoding transformer 4DT to the relay 4H, and contacts 81 and 82 of this relay are picked up so that contact 81 establishes the circuit of the relay 4PC, while contact 82 interrupts the circuit of the red lamp R and establishes the circuit of the yellow lamp Y of signal 4S. Accordingly, the signal 4S displays its caution indication when the train clears section 14T.

On the supply of energy to relay 4PC the contacts of this relay pick up so that the circuit traced above for supplying energy to line circuit I is interrupted, while a circuit including contact 75 of code transmitter ICT is established to supply energy to the line circuit I. This circuit is complete as one wire of line circuit I is connected through front contact 58 of relay 4PC, back contact 73 of relay 4HD, and code transmitter contact 75 to terminal C, while the other line wire is connected through front contact 51 of relay 4PC, back contact 72 of relay 4HD, front contact 48 of relay 13TR, and front contact 49 of relay 12TR to terminal B of the source of current. Accordingly, coded energy is supplied to line circuit I. The relay 2HD, like the relay 4HD, is immune to coded energy and its contacts become released at this time and establish the circuit of the relay 2CR so that relay 2CR responds to the coded energy supplied to the line circuit and energy is supplied through the decoding transformer 2DT to the relay 2H.

On picking up of the contacts of relay 2H its contact 82 establishes a circuit to energize relay 2DP to thereby maintain contact 80 of this relay picked up, while contact 57 of relay 2H picks up to establish a circuit to maintain the upper yellow lamp Y of signal 2S lighted and contact 58 picks up to interrupt the circuit of the lower red lamp and establish the circuit of the lower green lamp. Accordingly, when the eastbound train vacates section 14T, the signal 2S displays its approach medium instead of its caution indication.

When the eastbound train vacates section 14T, energy of reverse relative polarity is supplied over line circuit III to relay 6HD and its contact 60 picks up and interrupts the stick circuit of relay 6ES so that contacts 31 and 32 of this relay release. Release of contact 32 interrupts the circuit of code transmitter 1ICT, while release of contact 31 interrupts the circuit of the code transmitter contact and connects one wire of the line circuit II to terminal C of the source. At this time the other wire of the line circuit II is connected through contact 36 of relay 14TR, contact 35 of relay 15TR, and back contact 34 of relay 3WS to terminal B of the source, while contact 23 of relay 6HD establishes the circuit of the pole changing relay 6PC so that energy of normal relative polarity is now supplied to the line circuit II. In addition, as a result of energization of relay 6HD with energy of reverse polarity, the contacts 28 and 29 of this relay cooperate to establish the circuit of the

yellow lamp Y of signal 6S so that this signal provides its caution indication.

On the supply of energy of normal polarity to line circuit II the neutral contacts of relay 4HD pick up and contacts 38 and 39 of this relay cooperate to establish the circuit of the green lamp G of signal 4S, while contact 42 interrupts the circuit of decoding transformer 4DT and contacts 42 and 43 cooperate to establish a circuit to maintain relay 4PC energized. In addition, contact 40 interrupts the stick circuit of the directional stick relay 4ES, while contact 71 interrupts the circuit of the code transmitter ICT and contact 70 interrupts the circuit of the relay 4CR. As the relay 4CR no longer follows code, contact 81 of relay 4H releases, but energy is supplied to relay 4PC over contacts 42 and 43 of relay 4HD.

On picking up of the contacts of relay 4HD contact 73 interrupts the circuit of the code transmitter contact 75 and establishes connection from one wire of line circuit I through contact 48 of track relay 13TR and contact 49 of track relay 12TR to terminal B of the source of current, while contact 72 connects the other wire of the line circuit to terminal C. Accordingly, steady energy is supplied to the line circuit I, while as the contacts of relay 4PC are picked up, this energy is of normal polarity.

On the supply of this energy to relay 2HD its contacts pick up and interrupt the circuit of the relay 2CR, while relay 2H releases and polar contact 54 is shifted to its normal position. Accordingly, the circuits of the upper yellow and lower green lamps are interrupted and the circuits of the upper green and lower red lamps are established so that signal 2S again displays its clear signal.

Operation of system shown in Fig. 2 on movement of a westbound train through the track stretch.

Assuming that the track stretch is otherwise vacant, when a westbound train enters the single track stretch at the right of the passing siding, the supply of energy to the line circuit III is cut off and relay 6HD releases and its contact 20 establishes the circuit of the red or stop lamp R of signal 6S, while its contact 23 interrupts the circuit of the pole changing relay 6PC so that the energy supplied to line circuit II is changed from normal to reverse polarity.

On this change in the energy supplied to relay 4HD the polar contacts of this relay are shifted to their reverse positions and contacts 38 and 39 establish the circuit of the yellow lamp Y of signal 4S. In addition, at this time contact 43 interrupts the circuit of the pole changing relay 4PC and its contacts release and change the polarity of the energy supplied to line circuit I from normal to reverse.

As a result, the polar contact 54 of relay 2HD is shifted to its reverse position to thereby extinguish the upper green lamp and light the upper yellow lamp Y of signal 2S, while the lower red lamp R of this signal remains lighted to cause the signal to display its caution indication.

It will be seen, therefore, that when a westbound train is approaching the passing siding, the signal at the opposite end of the siding and governing traffic in the opposite direction, as well as the adjacent signal in the rear thereof display caution indications. Accordingly, an eastbound train approaching the passing siding will have ample warning of the approach of the

westbound train and will be able to stop before colliding with the westbound train.

When the westbound train enters section 15T, track relay 15TR releases and its contact 35 interrupts line circuit II so that the supply of energy over line circuit II is cut off and relay 4HD releases and its contact 38 establishes the circuit of the red or stop lamp R of signal 4S. At this time energy of reverse relative polarity continues to be supplied to line circuit I so that signal 2S continues to display its caution indication.

When the westbound train advances beyond signal 3S, track relay 14TR releases and relay 3WS is energized so that its contact 34 prevents the supply of energy to line circuit II. The relay 3WS is controlled in a manner similar to relay 4ES.

When the westbound train advances into section 13T, track relay 13TR releases and its contact 48 interrupts the supply of energy to line circuit I and relay 2HD thereupon releases and interrupts the circuit of relay 2DP so that contact 80 of relay 2DP releases and establishes the circuit of the upper red lamp R of signal 2S to thereby cause this signal to display its stop indication.

It will be seen, therefore, that the system shown in Fig. 2, like that shown in Fig. 1, is arranged so that when two trains traveling in opposite directions are in the vicinity of a passing siding, the signals operate to provide restrictive indications to insure adequate stopping distance for the trains, while when two trains traveling in the same direction are in the vicinity of a passing siding, the signals operate to provide adequate warning of the presence of the first train without unnecessarily requiring the second train to reduce its speed.

Although we have herein shown and described only two forms of apparatus embodying our invention, it is understood that various changes and modifications may be made therein within the scope of the appended claims without departing from the spirit and scope of our invention.

Having thus described our invention, what we claim is:

1. In combination, a stretch of railroad track over which traffic moves in both directions, said track stretch including a passing siding, a plurality of signals governing movement of trains in one direction through said track stretch, said signals including a first signal at the exit end of the siding, a second signal at the entrance end of the siding and a third signal in the rear of said second signal, said first and second signals being capable of displaying a clear, a caution and a stop indication, said third signal being capable of displaying a clear, an approach medium, a caution and a stop indication, a first line circuit substantially coextensive with said siding and governed by traffic conditions in the track stretch adjacent said siding, a second line circuit extending between the second and third signals and governed by traffic conditions in the track stretch intermediate said signals, means governed by traffic conditions in the track stretch in advance of the first signal and controlling the supply of energy to the first line circuit, said means being operative when said stretch in advance of the first signal is vacant to supply energy of a first character to said line circuit, when said stretch in advance of the first signal is occupied by a train moving in said one direction to supply energy of a second character to said first line circuit, and

when said stretch in advance of the first signal is occupied by a train moving in the other direction to supply energy of a third character to said first line circuit, electroresponsive means receiving energy over said first line circuit and controlling said second signal and also controlling the supply of energy to said second line circuit, said electroresponsive means being effective on the supply thereto of energy of said first character to condition said second signal to display its clear indication and to effect the supply of energy of said first character to the second line circuit, said means being effective on the supply thereto of energy of said second character to condition said second signal to display its caution indication and to effect the supply of energy of said second character to said second line circuit, and being effective when supplied with energy of said third character to condition said second signal to display its caution indication and to effect the supply of energy of said third character to said second line circuit, said means being effective when deenergized to condition said second signal to display its stop indication and to effect the supply of energy of said third character to said second line circuit, and electroresponsive means receiving energy over said second line circuit and controlling said third signal so as to cause said signal to display its clear, approach medium or caution indications according as energy of the first, second or third characters are supplied thereto and when no energy is supplied to said means to cause said signal to display its stop indication.

2. In combination, a stretch of railroad track over which traffic moves in both directions, said track stretch including a passing siding, a plurality of signals governing movement of trains in one direction through said track stretch, said signals including a first signal at the exit end of the siding, a second signal at the entrance end of the siding and a third signal in the rear of said second signal, said first and second signals being capable of displaying a clear, a caution and a stop indication, said third signal being capable of displaying a clear, an approach medium, a caution and a stop indication, a first line circuit substantially coextensive with said siding and governed by traffic conditions in the track stretch adjacent said siding, a second line circuit extending between the second and third signals and governed by traffic conditions in the track stretch intermediate said signals, means governed by traffic conditions in the track stretch in advance of the first signal and controlling the supply of energy to the first line circuit, said means being operative when said stretch in advance of said first signal is vacant to supply direct current of normal polarity to said first line circuit and being operative when said stretch in advance of said first signal is occupied to supply direct current of reverse polarity to said first line circuit, said means being operative when the train occupying said stretch in advance of said first signal is moving in said one direction to also supply alternating current energy to said first line circuit, electroresponsive means receiving energy over said first line circuit and controlling said second signal and also controlling the supply of energy to said second line circuit, said electroresponsive means being effective on the supply thereto of direct current of normal polarity to condition said second signal to display its clear indication and to effect the supply of direct current of normal polarity to the second line circuit,

said means being effective on the supply thereto of direct current of reverse polarity to condition said second signal to display its caution indication and to effect the supply of direct current of reverse polarity to said second line circuit, said means being effective when supplied with alternating current to effect the supply of alternating current to said second line circuit, said means being effective when deenergized to condition said second signal to display its stop indication and to effect the supply of direct current of reverse polarity to said second line circuit, and electroresponsive means receiving energy over said second line circuit and controlling said third signal so as to cause said signal to display its clear, approach medium or caution indications according as direct current of normal polarity, direct current of reverse polarity together with alternating current or direct current of reverse polarity alone is supplied thereto, and when no energy is supplied to said means to cause said third signal to display its stop indication.

3. In combination, a stretch of railroad track over which traffic moves in both directions, said track stretch including a passing siding, a plurality of signals governing movement of trains in one direction through said track stretch, said signals including a first signal at the exit end of the siding, a second signal at the entrance end of the siding and a third signal in the rear of said second signal, said first and second signals being capable of displaying a clear, a caution and a stop indication, said third signal being capable of displaying a clear, an approach medium, a caution and a stop indication, a first line circuit substantially coextensive with said siding and governed by traffic conditions in the track stretch adjacent said siding, a second line circuit extending between the second and third signals and governed by traffic conditions in the track stretch intermediate said signals, means governed by traffic conditions in the track stretch in advance of the first signal and controlling the supply of energy to the first line circuit, said means being effective when said stretch in advance of said first signal is vacant to supply direct current of normal polarity to said first line circuit and being effective when said stretch in advance of the first signal is occupied to supply direct current of reverse polarity to said first line circuit, a directional stick relay, means effective when a train moving in said one direction enters said track stretch in advance of said first signal to energize said directional stick relay, said relay being effective when energized to supply alternating current energy to said first line circuit, electroresponsive means receiving energy over said first line circuit and controlling said second signal and also controlling the supply of energy to said second line circuit, said electroresponsive means being effective when supplied with direct current of normal polarity to condition said second signal to display its clear indication and to effect the supply of direct current of normal polarity to said second line circuit, said means being effective when supplied with direct current of reverse polarity to condition said second signal to display its caution indication and to supply direct current of reverse polarity to said second line circuit, said means being also effective when supplied with alternating current to effect the supply of alternating current to said second line circuit, said means being effective when deenergized to condition said second signal to display its stop indication and to supply direct cur-

rent of reverse polarity to said second line circuit, and electroresponsive means receiving energy over said second line circuit and controlling said third signal so as to cause said signal to display its clear, approach medium or caution indications according as direct current of normal polarity, direct current of reverse polarity together with alternating current or direct current of reverse polarity alone is supplied thereto, and when no energy is supplied to said means to cause said third signal to display its stop indication.

4. In combination, a stretch of railroad track over which traffic moves in both directions, said track stretch including a passing siding, a plurality of signals governing movement of trains in one direction through said track stretch, said signals including a first signal at the exit end of the siding, a second signal at the entrance end of the siding and a third signal in the rear of said second signal, said first and second signals being capable of displaying a clear, a caution and a stop indication, said third signal being capable of displaying a clear, an approach medium, a caution and a stop indication, a first line circuit substantially coextensive with said siding and governed by traffic conditions in the track stretch adjacent said siding, a second line circuit extending between the second and third signals and governed by traffic conditions in the track stretch intermediate said signals, means governed by traffic conditions in the track stretch in advance of the first signal and controlling the supply of energy to the first line circuit, said means being effective when said stretch in advance of said first signal is vacant to supply direct current of normal polarity to said first line circuit and being effective when said stretch in advance of the first signal is occupied to supply direct current of reverse polarity to said first line circuit, a directional stick relay, means effective when a train moving in said one direction enters said track stretch in advance of said first signal to energize said directional stick relay, said relay being effective when energized to supply alternating current to said first line circuit, a line relay receiving energy over said first line circuit and effective when supplied with direct current of normal polarity to condition said second signal to display its clear indication and to supply direct current of normal polarity to said second line circuit, and when supplied with direct current of reverse polarity to condition said second signal to display its caution indication and to supply direct current of reverse polarity to said second line circuit, said relay being also effective when deenergized to supply direct current of reverse polarity to said second line circuit, a transformer having its primary winding connected to receive energy from said first line circuit and its secondary winding connected to supply energy to said second line circuit, and electroresponsive means receiving energy over said second line circuit and controlling said third signal so as to cause said signal to display its clear, approach medium, caution or stop indications according as direct current of normal polarity, direct current of reverse polarity together with alternating current, direct current of reverse polarity or no energy is supplied to said means.

5. In combination, a stretch of railroad track over which traffic moves in both directions, said track stretch including a passing siding, a plurality of signals governing movement of trains in one direction through said track stretch, said

signals including a first signal at the exit end of the siding, a second signal at the entrance end of the siding and a third signal in the rear of said second signal, said first and second signals being capable of displaying a clear, a caution and a stop indication, said third signal being capable of displaying a clear, an approach medium, a caution and a stop indication, a first line circuit substantially coextensive with said siding and governed by traffic conditions in the track stretch adjacent said siding, a second line circuit extending between the second and third signals and governed by traffic conditions in the track stretch intermediate said signals, means governed by traffic conditions in the track stretch in advance of the first signal and controlling the supply of energy to the first line circuit, said means being effective when said track stretch in advance of said first signal is vacant to supply direct current of normal polarity to said first line circuit and being effective when said stretch in advance of said first signal is occupied to supply direct current of reverse polarity to said first line circuit, said means being effective when the train occupying said stretch in advance of said first signal is moving in said one direction to alternately interrupt and establish the supply of energy to said first line circuit to thereby cause the energy supplied thereto to be coded, electroresponsive means receiving energy over said first line circuit and controlling said second signal and also controlling the supply of energy to said second line circuit, said means being effective when supplied with steady current of normal polarity to condition said second signal to display its clear indication and to supply direct current of normal polarity to said second line circuit, said means being effective when supplied with steady direct current of reverse polarity to condition said second signal to display its caution indication and to supply steady direct current of reverse polarity to said second line circuit, said means being effective when supplied with coded direct current to also condition said second signal to display its caution indication and to supply coded direct current to said second line circuit, and electroresponsive means receiving energy over said second line circuit and controlling said third signal so as to cause said signal to display its clear, approach medium, caution or stop indications according as steady direct current of normal polarity, coded direct current, steady direct current of reverse polarity, or no energy is supplied to said means.

6. In combination, a stretch of railroad track over which traffic moves in both directions, said track stretch including a passing siding, a plurality of signals governing movement of trains in one direction through said track stretch, said signals including a first signal at the exit end of the siding, a second signal at the entrance end of the siding and a third signal in the rear of said second signal, said first and second signals being capable of displaying a clear, a caution and a stop indication, said third signal being capable of displaying a clear, an approach medium, a caution and a stop indication, a first line circuit substantially coextensive with said siding and governed by traffic conditions in the track stretch adjacent said siding, a second line circuit extending between the second and third signals and governed by traffic conditions in the track stretch intermediate said signals, means governed by traffic conditions in the track stretch in advance of the first signal and controlling the supply of

energy to the first line circuit, said means being effective when said stretch in advance of said first signal is vacant to supply steady direct current of normal polarity to said first line circuit and being effective when said stretch in advance of said first signal is occupied to supply direct current of reverse polarity to said first line circuit, a directional stick relay, means effective when a train moving in said one direction enters said track stretch in advance of said first signal to energize said directional stick relay, said relay being operative when energized to include a contact of a coding device in the circuit for supplying coded energy to said first line circuit, electroresponsive means receiving energy over said first line circuit and controlling said second signal and also controlling the supply of energy to said second line circuit, said electroresponsive means being effective when supplied with steady energy of normal polarity to condition said signal to display its clear indication and to supply steady energy of normal polarity to said second line circuit, said means being effective when supplied with coded energy to condition said signal to display its caution indication and to supply coded direct current to said second line circuit, said means being effective when supplied with steady direct current of reverse polarity to condition said second signal to display its caution indication and to supply steady direct current of reverse polarity to said second line circuit, said means being effective when deenergized to condition said second signal to display its stop indication and to supply steady direct current of reverse polarity to said second line circuit, and electroresponsive means receiving energy over said second line circuit and controlling said third signal so as to cause said signal to display its clear, approach medium, caution or stop indications according as steady direct current of normal polarity, coded direct current, steady direct current of reverse polarity or no energy is supplied thereto.

7. In combination, a stretch of railroad track over which traffic moves in both directions, said track stretch including a passing siding, a plurality of signals governing movement of trains in one direction through said track stretch, said signals including a first signal at the exit end of the siding, a second signal at the entrance end of the siding and a third signal in the rear of said second signal, said first and second signals being capable of displaying a clear, a caution and a stop indication, said third signal being capable of displaying a clear, an approach medium, a caution and a stop indication, a first line circuit substantially coextensive with said siding and governed by traffic conditions in the track stretch adjacent said siding, a second line circuit extending between the second and third signals and governed by traffic conditions in the track stretch intermediate said signals, a directional stick relay, means effective when a train moving in said one direction enters said track stretch in advance of said first signal to energize said directional stick relay, means governed by said directional stick relay and by traffic conditions in said track stretch in advance of said first signal for supplying energy to said first line circuit, said means being effective when said stretch in advance of said first signal is vacant to supply energy of a first character to said first line circuit, when said stretch in advance of said first signal is occupied by a train moving in said one direction to supply energy of a second character

to said first line circuit, and when said stretch in advance of said first signal is occupied by a train moving in the other direction to supply energy of a third character to said first line circuit, electroresponsive means receiving energy over said first line circuit and controlling said second signal and also controlling the supply of energy to said second line circuit, said means being effective when supplied with energy of the first character to condition said second signal to display its clear indication and to supply energy of the first character to said second line circuit, when supplied with energy of said second character to condition said second signal to display its caution indication and to supply energy of said second character to said second line circuit, when

supplied with energy of said third character to condition said second signal to display its caution indication and to supply energy of said third character to said second line circuit, and when not supplied with energy to condition said second signal to display its stop indication and to supply energy of said third character to the said second line circuit, and electroresponsive means receiving energy over said second line circuit and controlling said third signal so as to cause said signal to display its clear, approach medium, caution or stop indications according as energy of the first, second or third characters or no energy is supplied thereto.
